UNITED STATES PATENT OFFICE.

LEANDER A. LAGERSTROM, OF BRANFORD, CONNECTICUT.

FOLDING CHAIR.

1,219,960.

Specification of Letters Patent. Patented Mar. 20, 1917.

Application filed May 3, 1916. Serial No. 95,195.

To all whom it may concern:

Be it known that I, LEANDER A. LAGERSTROM, a citizen of the United States, residing at Branford, in the county of New Haven and State of Connecticut, have invented certain new and useful Improvements in Folding Chairs, of which the following is a specification, reference being had to the accompanying drawings.

10 This invention relates to chairs, and particularly to chairs for theaters, lecture halls, and other places of like character.

The general object of the invention is the provision of a chair provided with a folding seat and a folding arm, the arm being operatively connected to the seat so that when the seat is folded up against the back the arm also folds up and when the seat is folded down the arm will be extended

20 into operative position.

A further object is to provide a theater seat with a single arm foldable into and out of operative position by the folding of the seat so that when the seats are placed together in rows, the single arm of one seat will act also as the arm of the next adjacent seat.

Other objects will appear in the course of the following description.

30 My invention is illustrated in the accompanying drawings, wherein:

Figure 1 is a perspective view of two of my improved chairs;

Fig. 2 is a side elevation of the chair; Fig. 3 is a face view of the chair shown in Fig. 1, one of the seats being shown as raised and the other seat being lowered and in section;

Fig. 4 is a perspective view of the seat and link 19;

Fig. 5 is a perspective view of the arm 17.

Referring to these figures, 10 designates the seat back which may be made of any suitable material and in any suitable manner but is preferably made in the form ordinarily found in theater seats, that is, as a more or less open framework which is attached to the floor of the theater or other auditorium by screws, the framework of one seat being connected to the framework of the seat adjacent. This supporting frame is formed to provide a back and is also provided with the outwardly projecting ears 11. The seat 12 at its rear end is formed with the laterally disposed projecting ears 13 and through the ears 11 and 13 passes

the pintle 14. Made part of the supporting frame of the seat and projecting upward therefrom is a supporting bracket 15 which is cut away to permit the passage of the pintle 14 and which supports the seat when the seat is turned down into a horizontal position.

The back 10 is formed with an ear 16 on one side and to this ear is pivoted the arm 17, this arm being formed with a downwardly extending flange through which the pivot pin passes, this flange being longitudinally slotted as at 18, said slot being downwardly angled at its extremity as at 18^a. A link 19 has a studded head at its upper end sliding within the slot 18 and at its lower end this link 19 is pivotally connected to a bar 20 which passes across the under face of the seat or is otherwise attached thereto and has one end upwardly extended and connected to the link 19 by means of a bolt, pin or other pivotal connection. The pivotal joint between the link 19 and the bar 20 is sufficiently stiff so as to resist rotational movement of the link 19 and assist in raising the arm when the seat is raised. In other words, as the seat moves upward rotating upon its pivot 11, the link 19 will be held in a position at right angles to the seat 12, until the seat and arm have reached such an angular position that the pivot pin connecting the link 19 with the arm 17 may slide downward in the slot 18.

The downwardly angled end 18^a of the slot 18 acts to resist the rearward movement of the pivot pin connecting the link 19 to the arm 17 so that when the arm 17 is moved upward, rearward movement of this pivot pin will be resisted and the pivot pin will remain in the forward end of the slot as the seat and arm move upward until a point is reached where the pivot pin commences to move downward because of the difference in length between the link 19 and the arm 17.

The operation of the improved seat will be obvious from the drawing. The turning down of the seat against the bracket 15 causes the arm to be brought into horizontal or operative relation and when the seat is turned upward the arm will take a vertical position, the link 19 folding in against the flange 18. It will be seen that each seat has one arm so that when the seats are placed together as in the theater, each seat will have an arm on each side of it but

one of these arms will be foldable with the seat to which it is connected. With the present type of theater seats the arm does not fold up and as a consequence 5 though the seat is folded or turned up the arm projects out into the aisle between the rows of seats and impedes the passage of persons.

It is obvious that under certain circumstances it will be necessary to provide chairs with two arms both operating in connection with the seats. I do not wish to limit myself to any specific construction of the chair back, the seat of the chair, or the 10 arm, except as hereafter referred to in the 15 claims, as it is obvious that the chair may be formed in any desired style.

Having described the invention, what I claim is:

- 20 1. In a chair of the character described, a back, a seat pivoted thereto for movement from a horizontal to a vertical position, means below the seat for supporting it in a horizontal position, an arm pivoted to the back and having a slot extending inward from its free end, a link operatively pivoted to the seat at a point in vertical alinement with the outer end of the arm when the latter is turned to a horizontal 25 position, the upper end of said link having a pivot member having sliding engagement with the stop, said link having a length less than the length of the arm, and means 30 for resisting the forward movement of the

link about its pivotal connection with the seat when the latter is raised.

2. A theater chair comprising a back disposed in approximately one plane, legs extending downward from the lower end of the back, said legs being disposed in planes 40 at right angles to the plane of the back and projecting forward slightly beyond the back, a seat having its rear end pivoted between said legs at the upper end thereof, a seat support, supporting the seat in a horizontal position, a lug projecting out from the back above the pivotal connection on the seat, an arm having a side face disposed against the outside face of said lug and pivoted thereto, said arm having a slot 45 extending inward from the free end of the arm, a link operatively pivoted to the seat and having a pivot member at its upper end having sliding engagement in said slot of the arm, said link being less in length 50 than the length of the arm and being pivoted to the seat in vertical alinement with the outer end of the arm when the latter is turned to a horizontal position, and means for resisting rearward movement of 55 the pivot member in said slot when the arm is raised.

In testimony whereof I hereunto affix my signature in the presence of two witnesses.

LEANDER A. LAGERSTROM.
